UNITED STATES PATENT OFFICE.

JESSE D. COTTRELL, OF CENTRAL FALLS, RHODE ISLAND.

LET-OFF MECHANISM FOR LOOMS.

SPECIFICATION forming part of Letters Patent No. 308,953, dated December 9, 1884.

Application filed May 29, 1882. (No model.)

To all whom it may concern:

Be it known that I, JESSE D. COTTRELL, of Central Falls, in the county of Providence and State of Rhode Island, have invented an 5 Improvement in Let-Off Mechanisms for Looms, of which the following is a specification.

My invention relates to the mechanism used in looms to gradually let off the warp from the 10 warp-beam, and is included in that class of let-off mechanisms known as "escapement let-offs."

The object of my invention is to provide an improved automatically-variable escapement 15 let-off which shall allow the warp-beam to rotate through a segment of its circumference corresponding to the amount of warp required to be drawn from the beam at any stage of its depletion, and which shall be capable of 20 operation under a light tension of the warp-threads, thus increasing the efficiency and lessening the wear of the engaging parts of the escapement.

My invention consists in the combination of 25 a wheel provided on its side with a circularly-arranged series of equidistant studs, and geared to the warp-beam, with a bar arranged for limited movement near the face of the stud-wheel, and provided with a fixed pallet and 30 with a pawl pivoted to the bar eccentrically to the axis of the stud-wheel, the fixed pallet being adapted to support one of the studs of the wheel against the transmitted tension of 35 the warp upon the warp-beam, and thus prevent the revolution of the stud-wheel, while the pawl is being caused to move from its point of contact with the bar to interior contact with one, two, or more adjacent studs by the movement of the bar in one direction, and to 40 release the retained stud and allow the stud-wheel to turn for the full limit of the former movement of the pawl from its seating-point on the bar, when the bar is caused by the movement of the loom to move in a reverse 45 direction.

Figure 1 represents a partly-sectional side view of a loom provided with my improvement, and shows the relative position of the parts of the let-off mechanism at the extreme 50 forward beat of the lay. Fig. 2 represents a partly-sectional detail view of the same, show-

ing the relative position of the parts of the let-off mechanism when the lay is in its backward position. Figs. 3, 4, and 5 are detail views of the mechanism. Fig. 6 represents a 55 partly-sectional side view of a loom provided with a modification of my improvement. Fig. 7 is a detail view showing a modification of the escapement devices.

In the drawings, A represents the side frame 60 of a loom, the breast-beam being at A' and the warp-beam at B. Secured to the warp-beam is a gear-wheel, B', (shown in Fig. 3, and also shown by a dotted circle in Fig. 1,) adapted to mesh with a pinion, C, placed 65 upon the inner end of the shaft D, passing through bearings secured to the frame. The outer end of the shaft D carries a gear-wheel, C', which meshes with a pinion, E, capable of revolving freely upon a short stud secured to 70 the frame of the loom. This gearing is shown in full lines in Fig. 3, and in dotted lines in Fig. 1, but to avoid confusion is omitted from Figs. 2 and 6.

To the pinion E is secured a wheel, F, having 75 a series of equidistant pins or studs, $a a'$ $a^2 a^3$, upon one side, near the edge, said pins being adapted to engage with a pallet, I, and pivoted pawl J, secured to the bar G, which extends diametrically across the face of the 80 wheel F, and is supported by the slide-bearings H H', connected to the loom-frame. The bar G is provided at one end with a slot, g, through which the screw b is passed, in order to hold the bar G to the slide-bearing H', and 85 the opposite end of the bar G is thinned from a shoulder, c, and received in the socket H.

To the upper side of the bar G is secured 90 the pallet I, held to the bar G by the bolt d, which may be loosened to permit the removal of the pallet for the purpose of change or repair, and to the side of the bar G, at a point which lies to one side of the axis of the wheel F, is pivoted the bell-crank pawl J, the upper or vertical arm, e, of which is connected 95 to the arm K of the whip-roll shaft L by means of the slotted link M. The slot in the link M serves to make provision for the whip-roll to take up the slack of the warp, when the harness changes, without at the same time imparting movement to the pawl, the said slot permitting of the vibration to a limited ex-

tent of the arm K without affecting in any way the movement of the pawl. The arm N, held loosely upon a stud, N', attached to the loom-frame, and thrown forward by the tension of the coiled spring O, Fig. 3, bears at its upper end against the projecting point k on the back of the arm e of the pawl, thus tending to force the pawl to the position shown in Fig. 1, and to force the bar G to its extreme forward position, in which position the bar will be held against the action of the spring-arm N by suitable stops, which may be either the shoulder c and slide-bearing H or the end of slot g and screw b.

15 The arm P, which is pivoted to the frame of the loom at the point f, is connected to the arm K of the whip-roll shaft by means of the connecting-rod Q, around which is placed the tension-spring R, held upon the rod Q between the adjustable collar h on the rod and the bracket i, secured to the loom-frame.

To the front of the sword T of the lay is secured the laterally-projecting stud U, which, by engagement with the lower end of the arm P during the forward movement of the lay, serves to elevate the whip-roll S, and prevent the forward movement thereof under the strain on the warp at the beat of the reed upon the weft, as shown in Fig. 1. The pawl W, 25 pivoted to the loom-frame, engages with the teeth of wheel F, and serves to prevent backward movement from being imparted to the wheel by the action of the spring O and pawl J in the backward movement of the bar G 30 when weaving very light goods.

The operation of the mechanism will be as follows: When the lay of the loom is in the forward position shown in Fig. 1, the lever P will be carried forward by the stud U upon 40 the lay, and the arm K of the whip-roll shaft L, which is connected with said lever P by the rod Q, will be drawn into the position shown in said figure, and prevented from moving backward under the strain exerted by the 45 warps on the whip-roll. While said arm and the parts connected therewith are maintained in this position, one of the studs, as a of the wheel F, will rest on the upper side of the projection r, formed on the lower or horizontal 50 arm of the pawl J, which projection will also rest against the upper surface of the bar G. Now, when the lay is carried back by the continued movement of the cranks V to the position shown in Fig. 2, and the stud U is dis- 55 engaged from the lever P, the tension of the warp-threads will be allowed to draw the whip-roll S forward, thus imparting a backward movement to the arm K, which movement, transmitted to the bell-crank pawl J by the 60 slotted connecting-link M, will cause the pawl J and bar G to move backward until the end of the pawl is drawn from under the stud a of the wheel F, when the stud will drop by the slight movement of the wheel to the upper 65 surface of the pallet I, upon which the stud will rest during the continued backward movement of the bar G. As soon as the pawl J

passes from under the spur a, the pawl will be forced to rise to contact with the under side of the stud a' by the action of the link M as 70 the arm K continues to move in a backward direction under the tension of the warp-threads.

The arm N, as before stated, is made to act against a projection, k, made at the back of the arm e of the pawl J, below the connecting-point m, for the link M, and the force of the upward movement exerted by the pawl against the studs of the wheel F may be controlled by the proper location of the projecting point k with respect to its distance from the connecting-point m, the upward pressure being diminished as the point k is made nearer to the point m, and the downward pressure exerted at the point of the pawl on its reverse movement being increased in the same ratio. When the 85 warp-beam is full, a sufficient quantity of warp will be permitted to unwind by the movement of wheel F a single tooth at a time, and in such case the tension of the warp-threads will only have to draw the bar G far enough to allow the pawl J to rise against the stud a', but when the warp-beam has become somewhat 90 depleted and smaller in diameter the bar G must be drawn back far enough to cause the pawl J to pass from under the stud a' and rise 95 into contact with the lower side of the stud a'', in order that a sufficient amount of warps may be unwound; and when the warp upon the beam has become nearly exhausted then the still further backward movement of the 100 bar G, which must be made to permit the warps to yield sufficiently at the opening of the shed of the warp, will cause the pawl to 105 pass from under the stud a'' and rise to contact with the under side of the stud a'', as shown in Fig. 2, the stud a still resting after the movement of pawl J from under the same and into engagement with stud a', a'', or a''' against the pallet I, which is shown in Fig. 2, by breaking away a portion of the bar G. Now, as 110 the crank V passes its back center and brings the lay toward the fell of the cloth, the change of the harness of the loom will slacken up the warp-threads and allow the spring R upon rod Q to impart a backward movement to the 115 whip-roll, thus allowing the bar G and pawl J to be brought forward by the action of the spring O upon the projecting point k on the arm e of the pawl through the arm N until the stud a is released from the holding-pallet 120 I. The end of the pawl at the same time moves forward in the upward inclined position (shown in Fig. 2) between the studs a'' and a'''. As soon as the bar G has progressed in 125 its forward movement far enough to allow the stud a to escape from the pallet I to the opening n in bar G, (shown in Figs. 2 and 4,) the wheel F will cease to be held, and will be caused to revolve by the tension of the warp-threads, and also by the action of the 130 spring-operated arm N, which, when the movement of the bar G is arrested, tends to turn the bell-crank pawl J upon its pivot o, and thus operates to turn the wheel F in case the

rotation of the wheel was not fully effected by the tension of the warp-threads. The pawl J will thus be brought again to the position shown in Fig. 1, and the warp-beam will have been moved through part of a revolution corresponding proportionately in extent with the movement of the wheel F. Upon every succeeding revolution of the crank-shaft of the loom the above-described operation of the let-off will be repeated with uniformity. The back of the arm e of the pawl above the bearing-point k, and connecting-point m of the link M is curved in order to present a cam surface to the action of the arm N when the lower or horizontal arm of said pawl J is forced to a more elevated or vertical position, which may be done for the purpose of clearing the projection r of the pawl from the studs of the wheel F, to allow the wheel F to be turned by hand in order to properly adjust the tension of the warp for the commencement of weaving, and in this case the pallet r of the pawl will pass between the studs to a position beyond the periphery of the wheel F.

25 A modification of my improved let-off mechanism by which it is adapted to the weaving of very light and flimsy goods is shown in Fig. 6, the specific change from the form shown in Fig. 1, and just described, consisting simply in the removal of the stud U from the lay-sword T. In this modification the force of the beat and tension of the warp-threads cause the backward movement of the pawl J and pallet I to the position shown in Fig. 6, which corresponds to the position represented in Fig. 2, and described in connection with that view, as being assumed at the backward movement of the lay. In the arrangement shown in Fig. 6, as soon as the reed moves back from the weft, 40 the slackening of the strain upon the warp-threads will allow the whip-roll S to be moved backward by the tension of the spring R upon the rod Q, thus causing the arms K and N, pawl J, and pallet I to be moved forward to a position corresponding with that shown in Fig. 45 1. This forward movement of the pawl J and pallet I will cause the forward movement of the wheel F for the space of the three studs a, a', and a'', or through the space of one, two, or 50 three studs, as the condition of the warp may at any time require. It will be seen that upon the removal of the stud U the timing of the movements of the pawl J and pallet I will be materially changed with relation to the movement of the lay, so as to let off the warp from the warp-beam at an entirely different point in the movement of the crank-shaft of the loom from that at which the warp is unwound when the devices are arranged as shown in Figs. 1 and 55 2, and therefore under a different condition in the tension of the warp-threads, which difference tends to adapt the loom for light weaving.

60 A modification in the application of the spring O for moving the pawl J and pallet I

is shown in Fig. 7, in which the spring O is placed around a rod, N', which is jointed to the arm e of the pawl J at the point k, and is arranged to pass loosely through a bearing in the stand H', the spring being held between 70 the inner face of the stand H' and the adjustable collar t upon the rod N'.

I do not claim, broadly, the combination of an escapement-wheel with a reciprocating pallet and pawl, as such a combination is 75 shown and claimed in a patent granted to me April 15, 1884, No. 296,927.

Having fully described my invention, I claim—

1. The combination of the warp-beam B and 80 the wheel F, geared to the warp-beam and provided on its side with a circular series of studs, a a' a'' a''', with the bar G, arranged for a limited movement near the face of the wheel F, and provided with the fixed pallet I and the pivoted pawl J, the whip-roll, means for connecting said whip-roll with the pawl J, and a spring for operating the whip-roll in opposition to the strain of the warp, substantially as described. 90

2. The combination of the warp-beam, a wheel provided with a circular row of studs projecting from its side, a mechanism adapted to rotate the same from the warp-beam, a whip-roll, a pallet, and a pivoted bell-crank pawl, 95 means for holding the same to the face of the stud-wheel, and mechanism for imparting a movement from the whip-roll to the pivoted pawl in one direction, with a spring for imparting a pivotal movement to the pawl in the opposite direction to assist in turning the stud-wheel and warp-beam, substantially as described. 100

3. The combination of the warp-beam B and 105 the wheel F, geared to the warp-beam, and provided upon its side with a circular row of studs, with the bar G, arranged for a limited movement near the face of the wheel F, the fixed pallet I and the pivoted bell-crank pawl J, the lever N, spring O, the slotted link M, 110 whip-roll S, whip-roll arm K, connecting-rod Q, spring R, arm P, the lay, and stud U, substantially as described. 110

4. The combination of a warp-beam, a wheel provided with a circular row of studs projecting from its side, a mechanism adapted to rotate the same from the warp-beam, a whip-roll, a pallet, and a pivoted bell-crank pawl, means for holding the same at the face of the stud-wheel, a mechanism for imparting a movement 115 from the whip-roll to the pallet and pawl in one direction, with means for moving the pallet and pawl in the opposite direction, and a fixed pawl for preventing the backward movement of the stud-wheel, substantially as described. 120 125

JESSE D. COTTRELL.
